Application June 17, 1948, Serial No. 147,019

Term of patent 14 years

(Cl. D21—6)

To all whom it may concern:

Be it known that I, Hans K. Lorentzen, a citizen of the United States and a resident of Montclair, in the county of Essex and State of New Jersey, have invented a new, original, and ornamental Design for Combined Venetian Blind Head Bar and Installation Brackets Assembly, of which the following is a specification, reference being had to the accompanying drawing, forming part thereof.

Figure 1 is a prospective view of a combined Venetian blind head bar and installation brackets assembly, showing my new design.

Figure 2 is a rear elevation of the same.

I claim:

The ornamental design for a combined Venetian blind head bar and installation brackets assembly, substantially as shown.

HANS K. LORENTZEN.
